IGNITION SYSTEM AND CONTROL FOR BURNER AND CONVEYOR

Filed Sept. 28, 1961

A diagram of a branched graph structure. It consists of several nodes connected by lines. Node 51 is at the top left, connected to node 52. Node 52 is connected to node 54, which is a central circle. Node 54 is also connected to node 56, which is at the bottom. Node 56 is connected to node 53 at the top right. Node 53 is connected to node 54. There is also a line from node 54 to node 55, which is at the top right. Node 55 is connected to node 53.

IGNITION SYSTEM AND CONTROL FOR
BURNER AND CONVEYOR

Joseph Leo La Pointe, Detroit, Mich., assignor to Hupp Corporation, Cleveland, Ohio, a corporation of Virginia
Filed Sept. 28, 1961, Ser. No. 141,379
11 Claims. (Cl. 263—6)

This invention relates to an ignition system or control circuit for a burner or conveyor, and especially to a flame sensing element, an electrode element and control means responsive to relative displacement of one of said elements for automatically cutting off fuel to said burner and/or stopping a conveyor carrying work pieces heat processed by said burner.

An object of the present invention is to provide a control circuit for a burner means, having a flame sensing element means, an electrode element means, and means responsive to displacement of at least one of said element means out of a given position for cutting off the supply of fuel to said burner means.

A further object of the present invention is to provide a control circuit for a conveyor means sequentially moving work pieces past a heat processing burner means, comprising a flame sensing element means, an electrode element means, and means responsive to displacement of at least one of the element means out of a given position for de-energizing drive to said conveyor means.

A further object of the invention is to provide an ignition system for a burner using one or both of the control circuits mentioned in the two preceding paragraphs that will automatically ignite the burner, has electronic means responsive to the combustion of gas in the burner to turn off the gas igniter, rapidly senses and responds without delay to the presence or absence of a flame at the burner, will shut off flow of fuel to the burner if the burner fails to ignite, will automatically re-ignite the burner after the flame has blown out, and/or has means responsive to failure of combustion of fuel in the burner to actuate relay means and shut off a solenoid operated valve to discontinue flow of fuel to the burner.

A further object of the invention is to provide a burner control, conveyor control, or ignition system characterized by its compact construction; minimum number of component parts; low manufacturing cost; fail safe operation; ease of use; long, trouble-free wear life; and safety features providing safe operating conditions.

These and other objects of the present invention will become more fully apparent by reference to the appended claims as the following detailed description proceeds in reference to the accompanying drawings wherein:

FIG. 1 is a schematic representation of a first form of a present invention; and

FIG. 2 is a schematic representation of a portion of a second form of the present invention.

This is an improvement on the invention disclosed in the co-pending application filed by John J. Fannon, Jr. and Joseph Leo La Pointe on September 28, 1961, Serial No. 141,479, and entitled "Ignition System and Control For Fuel Burner."

FIG. 1 shows the first form of the invention. FIG. 2 shows a circuit component adapted to be substituted in FIG. 1, for the component shown therein at the correspondingly numbered terminals, to provide said second form of the invention with the remainder of FIG. 1. The first form of the invention in FIG. 1 will be described in complete detail first before later describing the second form of the invention in FIG. 2.

The control circuits, ignition systems, and control systems for a conveyor and burner in the present invention are especially adapted for heat processing conveyor moved

work pieces in a safe manner, and are especially adapted for use on infrared radiant heater burners of the type shown in the G. Schwank United States patents, Nos. 2,775,294 and 2,870,830.

FIG. 1 discloses a conventional solenoid operated gas valve 14 for supplying and controlling the flow of combustible fluid fuel, such as gas, from supply line 18A to fluid fuel burner means 18. Air is aspirated into burner 18 by the gas and burned adjacent one surface of the burner to form flame 19. Burner housing 18 is made of metal or other electrically conductive material. Gas or fuel valve 14 is a conventional shut-off valve having valve 14A to open or close a port to control the flow of gas. Valve element 14A is urged to the valve closed position by a spring (not shown). Solenoid 13, upon energization, is effective to open valve element 14A in valve 14 against the action of the spring into the valve open position, while de-energization of solenoid 13 permits the spring to move valve element 14A to the valve closed position.

Time delay relays V2 and V3 are of a conventional type in which heater elements 16 and 11 therein respectively are provided to heat to a pre-selected temperature in a pre-selected time so as to open or close associated respective contacts or switches 15 and 12 at the pre-selected time and temperature.

Conveyor 30 has endless conveyor belt 31 driven by motor 32 to conveyor work pieces or parts 33 in the direction of the arrow under flame 19 for heat processing of these parts 33.

Although any suitable circuit components may be used, it has been found in one suitable installation that a proper mode of operation is achieved by using components of the following sizes: transformer T1 has a 115 volt, 60 cycle primary winding or coil T1-P, 190 volt A.C. across secondary terminals T1-1 and T1-2 at no currents conditions, 6.3 volts 2 amps across secondary terminals T1-3 and T1-4, 24 volts across secondary terminals T1-4 and T1-5, 100 ma. across terminals T1-4 and T1-6, 160 volts across terminals T1-5 and T1-6, and secondary coil T1-S having terminals T1-1, T1-2, T1-3, T1-4, T1-5 and T1-6; transformer T2 has a 5000 ohms primary coil and 333 ohms secondary coil, and has maximum impressed voltage across the primary coil of 2 volts and 400 microamps and across the secondary coil of 0.15 volt and 0.50 microamp; glow coil igniter transformer T3 has a 110 volts, 2.5 amps primary coil and a 2.5 volts, 11 amps secondary coil; resistance Z1 is a 3 to 10 megohms $\frac{1}{2}$ watt resistor; grid protector resistance Z2 is a 240 K ohms $\frac{1}{2}$ watt resistor; resistance Z3 is a 2300 ohm potentiometer serving as a bias sensitivity control for tube V4; resistance Z4 is a one megohm $\frac{1}{2}$ watt resistor; igniter coil 10 is a Nichrome heater element flow coil; thyratron tubes V1 and V4 are each a 2D21 thyratron, or any equivalent electronic valve with or without ground G2; and probe 20 is a metal probe constructed of Inconel or other suitable material.

The mode of operation should be readily apparent after considering the following description.

Closing main switch S1 energizes the primary and secondary coils of transformer T1 and igniter glow coil, positioned adjacent burner 18 for causing flame 19. Alternating current power is supplied through A.-C. power lines L1, L2 to primary coil T1-P and secondary coil T1-S of transformer T1 after closing main switch S1 for supplying power to tubes V1 and V4. Closing switch S1 also energizes or supplies alternating current power to igniter glow coil or igniter 10 by forming Circuit No. 1 through line L1, transformer T3, igniter glow coil 10, normally closed contact R1-1 of relay R1 as a switch means in the igniter energizing circuit, and line L2.

Since tubes V1 and V4 disclosed herein require approximately 10 to 15 seconds warmup time before they can operate, a suitable time delay is provided in the circuit by keeping open contact 12 of time delay relay tube V3 to prevent power being applied to gas valve solenoid 13 until after warmup has occurred. Closing main switch S1 energizes time relay relay tube V3 by forming Circuit No. 2 through line L1, heater element 11 of time delay relay tube V3, and line L2. After the 10 to 15 seconds time delay has elapsed, heater element 11 of tube V3 closes its normally open contacts 12: (1) to energize solenoid 13 to open gas control valve 14 to permit gas to flow from gas line 18A into burner 18 by forming Circuit No. 3 electrically connected in parallel with primary coil T1-P of transformer T1 through line L1, normally open contact 12 now closed, normally closed contact 15, normally closed contact R2-1 of relay R2, valve solenoid 13, and line L2; and (2) to energize time delay relay tube V2 by forming Circuit No. 4 through line L1, normally open contact 12 now closed, heater element 16 of tube V2, normally closed contact R1-1 of relay R1, and line L2.

Now, energized igniter 10 will ignite the gas mixture now permitted to flow from burner 18 through open valve 14 and will produce flame 19.

After the gas is ignited, flame 19 completes an electrical path causing thyratron tube V1 to conduct, relay R1 to be energized, and igniter 10 and time delay relay heater element 16 to be de-energized. Tube V1 has cathode heater 22 energized by a circuit from transformer secondary winding terminals T1-3 and T1-4. Flame 19 forms Circuit No. 5 through series connected transformer tap T1-1, resistance Z1, junction Z4, burner housing 18, flame 19, flame sensing element means or probe 20 located adjacent burner 18 contiguous to or in flame 19 from burner 18, primary coil of transformer T2, and transformer secondary tap T1-6. Circuit No. 5 is energized by secondary coil T1-S and electrically connected to grid 25 at junction Z4. The voltage pulse or the potential at junction Z4 produced by Circuit No. 5 is now sufficiently positive relative to cathode 23, because of the IR drop across resistance Z1, so that a glow discharge takes place between cathode 23 and starter anode or grid 25 so the gas is ionized in thyratron tube V1 and the tube conducts, during each half cycle that anode 24 is positive, so electronic valve V1 is actuated to energize relay R1 by forming Circuit No. 6 energized by secondary coil T1-S through transformer secondary terminal T1-5, cathode 23 of thyratron tube V1, anode 24 of tube V1, relay coil R1-C of relay R1, and transformer secondary terminal T1-6. Sensing element 20, electrically connected to grid 25, thus senses the presence of flame 19 by conduction of an electrical current along a path through flame 19 to control the conduction action of tube V1 by grid 25. Rectifier or diode 26, located in series with thyratron V1, is in parallel with relay coil R1-C to prevent relay chatter because tube V1 conducts only during the positive half cycles, but any suitable unidirectional electronic valve, such as a condenser, may be so placed in parallel with relay coil R1-C for this same purpose. Under normal conditions, Circuit No. 5 does not have sufficient current flowing through transformer T2, because of the resistance of flame 19, to cause grid 40 of tube V4 to be sufficiently positive for causing tube V4 to conduct. Energizing relay coil R1-C opens switch means or normally closed relay contact R1-1 now: (1) to break Circuit No. 1 to de-energize and cut off power to igniter 10 for conservation purposes when a flame 19 is present and thyratron V1 is energized, and (2) to break Circuit No. 4 to de-energize heater element 16 of time delay relay tube V2. Gas valve 14 is open, igniter 10 is de-energized, heater element 16 of time delay tube V2 is de-energized, and flame 19 maintains this condition of operation.

Here, three electrode elements are provided in Circuit No. 5, including burner housing element means 18, work

piece element means 33 through conveyor element means 30, and probe element means 20. If desired, a second probe, electrode or structural element means, similar to probe 20, can be located in flame 19 and directly electrically connected to junction Z4 and ground G1 with burner 18 and conveyor 30 eliminated from Circuit No. 5.

If flame 19 goes out, tube V1 stops conducting, relay R1 is de-energized igniter 10 is re-energized, and heater element 16 of time delay relay tube V2 is re-energized. If flame 19 goes out, lack of flame 19 causes sensing element 20 to control the action of tube V1 by breaking Circuit No. 5 so that the positive potential at junction Z4 is reduced to reduce the positive bias on grid 25 of tube V1 to prevent tube V1 from conducting. Since tube V1 stops conducting, Circuit No. 6 is broken to de-energize relay coil R1-C and close its normally closed contact R1-1. Closing switch means or relay contact R1-1 now: (1) energizes or applies power to igniter 10 by reforming Circuit No. 1 when flame 19 is absent, and (2) energizes heater element 16 of time delay relay tube V2 by reforming heater element energizing Circuit No. 4.

If flame 19 is absent, burner 18 does not re-ignite, or flame 19 is not restored within a predetermined period of time established by thermal time delay switch means or relay tube V2, gas valve 14 is closed. After time delay relay tube V2 times out, its energized and heated heater element 16 opens its normally closed bimetal switch or contact 15 located in valve energizing Circuit No. 3 to break Circuit No. 3 to de-energize solenoid 13 and thus to close gas valve 14 to cut off the supply of fuel to burner 18.

It should also readily be apparent that if, when Circuit No. 4 was first formed as first described heretofore, flame 19 was not produced within the predetermined period of time established by heater element 16 of time delay relay tube V2, heater element 16 opens normally closed contact 15 to break Circuit No. 3 to de-energize solenoid 13 to close valve 14 in the same manner to shut off the supply of gas to burner 18.

Conveyor 30 has endless work piece conveyor belt 31 driven by a drive means, including motor 32, to convey work pieces or parts 33 in the direction of the arrow under flame 19 for heat processing sequentially parts 33 moved by conveyor belt 31. Motor 32 is energized in any suitable manner, such as by forming Circuit No. 7 through line L1, motor 32, normally closed relay contact R3-1 of relay R3, and line L2.

When conveyed work piece parts 33, by becoming displaced on the conveyor line, jam against flame probe 20 so as to risk damage to burner 18 mounted on the oven wall and other components of the apparatus, a safety circuit protects both work pieces 33 and the conveyor by automatically stopping the heat processing of articles 33 by de-energizing conveyor motor 32 and closing fuel valve 14. When parts 33 are not so jammed and tube V1 is sensing the "on condition" of flame 19 by probe 20 being located in a given normal relative position relative to burner 18, conveyor 30 and work pieces 33, a voltage of 0.15 volt at 50 microamps may be crossing flame 19 to grounded burner 18, or to the aforementioned second probe or electrode element means, because of the high impedance of 3.8 megohms with a frequency of 60 cycles at flame 19. Then there is not sufficient current in Circuit No. 5 and transformer T2 to cause tube V4 to conduct. However, when piled up work pieces 33 on conveyor 30 cause flexible flame probe, electrode or flame sensing element means 20 to be displaced out of its given normal position relative to burner 18, and to engage and to ground against any of the other electrodes or structural element means, such as grounded metal burner housing element means 18, through work piece element means 33 and grounded metal conveyor element means 30, or against the aforementioned second probe or electrode element means, a short is provided in Circuit No. 5 instead of the high impedance condition across flame 19 so as to

change the electrical resistance in the path of Circuit No. 5 contiguous to flame probe 20. This may now cause a 2 volts, 400 microamperes signal to flow through Circuit No. 5 and the primary of transformer T2. The potential difference between control grid 40 and cathode 41 of thyratron V4 is the summation of two potentials; (1) the potential from secondary terminal T1-5 to tap 43 caused by the IR drop across resistance Z3 energized by transformer secondary terminals T1-4 and T1-5, and (2) the potential across the secondary coil of transformer T2. When the current in Circuit No. 5 is large, the potential across the secondary coil of transformer T2 is correspondingly large so that the potential difference between cathode 41, heated in the same manner as cathode 23, and control grid 40 of thyratron tube V4 is sufficiently positive on grid 40 to cause tube V4 to fire or conduct. Tap 43 is manually adjustable to provide sensitivity control so as to control firing of tube V4 at any desired degree of grounding of probe 20. When tube V4 fires, relay R2 is energized by forming Circuit No. 8 through transformer secondary terminal T1-5, cathode 41 of tube V4, anode 42 of tube V4, relay coil R2-C of relay R2, and transformer secondary terminal T1-6. Rectifier or diode 44, in parallel with relay coil R2-C, prevents chattering of the relay coil in the same manner as earlier described for rectifier 26. Energizing relay R2 now: (1) opens normally closed relay contact R2-1 to break Circuit No. 3 to de-energize solenoid 13 and close gas valve 14, and (2) closes normally open relay contact R2-2 to sound warning buzzer 45 and to energize relay R3 to open relay contact R3-1 to break Circuit No. 7 to de-energize conveyor driving motor 32 to stop conveyor 30 by forming Circuit No. 9 through line L1, normally open contact 12 now closed, normally closed contact 15, normally open relay contact R2-2 now closed, warning buzzer 45, conveyor stop relay coil R3-C, and line L2. Now, conveyor 30 is stopped and no flame 19 exists so that the whole apparatus is shut down until the jamming and grounding of probe 20 is corrected.

The second form of the invention is shown in FIG. 2. It is exactly the same as the FIG. 1 form except that the circuitry in FIG. 2 between terminals 51, 52 and 53 (including manually operated switch 55 and neon glow lamp 56 or other suitable warning light) is substituted for tube V2 in FIG. 1 at terminals 51, 52 and 53. The sequence of operation and of circuit forming and breaking occurs the same as before described but with the following exceptions. First, Circuit No. 3 is now not formed until after switch 55 is manually closed so that the gas valve and ignition are manually operated, such as on a domestic oven or broiler igniter. Second, if any of these conditions: (1) flame 19 goes out after once lit, or (2) flame 19 is not originally produced have occurred so as to break sequentially Circuits Nos. 5 and 6 to de-energize relay coil R1-C, normally closed relay contact R1-1 will close to reform: (1) Circuit No. 4 so lamp 56 will now be energized, instead of heater element 16 of tube V2, to indicate lack of flame 19 and to indicate "ignition on" to the apparatus operator, and (2) Circuit No. 1 to re-energize igniter 19. After lamp 56 has been lit for a predetermined period of time, the operator may manually open switch 55 to break Circuit No. 3 to de-energize solenoid 13 to close gas valve 14 in the same manner as heating of element 16 in FIG. 1 automatically opened switch 15 in tube V2 to break Circuit No. 3 after the time delay.

It may now be readily appreciated that the control circuits and ignition systems in FIGS. 1 and 2 invention forms are effective as safeguards to assure that gas burner 18 is operating properly when gas valve 14 is open, to automatically ignite and re-ignite burner 18, and to automatically shut off the flow of fuel to burner 18 and to stop conveyor 30 when work pieces 33 jam up to cause grounding of flame probe 20. The apparatus is simple in construction, requires a minimum number of operating parts, is compact, operates quickly without undue delay, is fail

safe in that failure of substantially any of the component parts will operate to discontinue the flow of gas to burner 18 and require trouble shooting of the circuit to locate and repair the fault, prevents improper processing of work pieces 33 by shutting off burner fuel and stopping conveyor 30 if jam up occurs, and has a substantially long, trouble free wear life.

The invention may be embodied in other specific forms without departing from the spirit or essential characteristics thereof. The present embodiments are, therefore, to be considered in all respects as illustrative and not restrictive with the scope of the invention being indicated by the appended claims rather than by the foregoing description, and all changes which come within the meaning and range of equivalency of the claims are therefore intended to be embraced therein.

What is claimed and desired to be secured by U.S. Letters Patent is:

1. A control system for a fluid fuel burner means, comprising a structural element means providing part of the structure of said system and burner means and a flame sensing element means located in a given relative position contiguous to the location of a flame from said burner means, means responsive to flame sensing by said flame sensing element means for providing ignition at said burner means when the flame is absent, and means responsive to displacement of at least one of said element means out of said given relative position to a fuel cut-off position into contact with the other element means for cutting off the supply of fuel to said burner means.

2. In combination, a work piece conveyor means; drive means for moving such conveyor means; a burner means for heat processing sequentially work pieces moved by said conveyor means; and a control system for said conveyor means, comprising a structural element means providing part of said combination and a flame sensing element means located in a given relative position contiguous to the location of a flame from said burner means, means responsive to flame sensing by said flame sensing element means for providing ignition at said burner means when the flame is absent, and means responsive to the displacement of at least one of said element means out of said given relative position to a conveyor drive de-energizing position for de-energizing the drive means to said conveyor means.

3. An apparatus for heat processing of articles by a burner means, comprising a structural element means in said apparatus and a flame sensing element means located in a given relative position contiguous to the location of a flame from said burner means to sense the presence of the flame by an electrical path through said flame between said element means, means responsive to flame sensing by said flame sensing element means for providing ignition at said burner means when the flame is absent, and means responsive to displacement of at least one of said element means out of said given relative position and toward the other element means to reduce the electrical resistance in said path contiguous to said flame sensing element means for automatically stopping the heat processing of articles.

4. An apparatus for heat processing articles by a burner means controlled by an ignition system, comprising a work piece conveyor means; drive means for moving said conveyor means; a burner means for heat processing sequentially work pieces moved by said conveyor means; and a control and burner ignition system for said conveyor means and burner means, comprising an igniter adjacent said burner means, a structural element means providing part of said apparatus and a flame sensing element means located in a given relative position contiguous to the location of a flame from said burner means to sense the presence of the flame by an electrical path through said flame, means responsive to flame sensing by said flame sensing element for energizing said igniter when the flame is absent, means responsive to flame sensing by said

flame sensing element means for de-energizing said igniter when the flame is present, and means adapted to be responsive to the displacement by a work piece of said sensing element means out of said given position to change the electrical resistance in said path contiguous to said flame sensing element means for shutting off the supply of fuel to said burner means and for automatically de-energizing and stopping said conveyor means.

5. An apparatus, as set forth in claim 4, with said structural element means being said burner means.

6. An apparatus, as set forth in claim 4, with each of said element means being a flame probe adapted to be located in said flame.

7. An apparatus, as set forth in claim 4, with said structural element means being said conveyor means and adapted to be any work pieces thereon.

8. An apparatus, as set forth in claim 4, with fuel shut-off means including fuel switch means for controlling a fuel valve and being adapted to be opened to shut off said fuel after a predetermined period of time in the event that the burner does not ignite.

9. An apparatus, as set forth in claim 8, with thermal time delay switch means including a heater element energized when the flame is absent and including said fuel switch means being normally closed and adapted to be

automatically opened by energizing said heater element for said predetermined period of time.

10. An apparatus, as set forth in claim 8, with a warning light energized when the flame is absent, and said fuel switch means being manually operable after said warning light has been lit for said predetermined period of time.

11. An apparatus, as set forth in claim 4, with said structure element means being said burner means and adapted to be said conveyed work pieces straddling said flame sensing element, so that any displacement of said flame sensing element by a work piece against either of said structural elements will shut off the fuel supply and stop said conveyor means.
